UNITED STATES PATENT OFFICE

HOWARD E. HODGSON, OF WAUWATOSA, WISCONSIN, ASSIGNOR TO CUTLER-HAMMER, INC., OF MILWAUKEE, WISCONSIN, A CORPORATION OF DELAWARE

SNAP OPERATING MECHANISM

Application filed April 6, 1931. Serial No. 527,920.

This invention relates to improvements in snap operating mechanism for devices such as electric switches.

An object of the invention is to provide an improved quick acting operating mechanism for devices such as electric switches which is of sturdy construction and which comprises a relatively small number of parts capable of cheap manufacture and ready assembly.

10 Another object is to provide an electric switch having an improved operating mechanism associated therewith which provides for operation of the switch between given circuit controlling positions with a snap action and which also serves to positively lock the switch in either of such positions.

Another object is to provide an improved switch of the toggle operated type which is adapted to be actuated by a traveling nut or 20 similar device.

Various other objects and advantages of the invention will hereinafter appear.

The accompanying drawings illustrate an embodiment of the invention which will now 25 be described, it being understood that various modifications may be made in the embodiment illustrated without departing from the spirit and scope of the appended claims.

In the drawings,

30 Figure 1 is a front elevational view of a switch having an operating mechanism embodying the invention associated therewith.

Figs. 2, 3 and 4 are views similar to that shown in Fig. 1, illustrating the operating 35 mechanism in different positions.

Fig. 5 is a plan view of certain of the parts of the switch operating mechanism shown in Fig. 1, and

Fig. 6 is a side elevational view of one of 40 the sets of switch contacts shown in Fig. 1.

Referring to the drawings, the same illustrates a control switch including a movable contact element 1 which is provided with bridging contacts 2 and 3 arranged to co- 45 operate with two pairs of stationary contacts 4-4 and 5-5, respectively. Bridging contacts 2 and 3 are each yieldingly secured to the upper face of an insulating bar 6 by a spring pressure device 7 of the construction 50 shown in Fig. 6 and the bars 6 are secured

to opposite ends of a lever 8 which is rotatably mounted intermediate its ends upon a shaft 9. Shaft 9 is supported at opposite ends by a U-shaped bracket 10 and the lower end of said bracket carries an insulating plate 11 upon which the stationary contacts 4-4 and 5-5 are mounted. 55

Contact element 1 has an operating mechanism associated therewith including an operating member 12, a pair of similar toggle joints 13 and 14 and a spring pressure device 15. Operating member 12 is rotatably mounted upon a shaft 16 which is supported at opposite ends by bracket 10, and as hereinafter set forth said operating member when moved in opposite directions between given extreme positions acts through the medium of the toggle joints 13 and 14 and spring pressure device 15 to effect rotation of contact element 1 in opposite directions with 65 a snap action.

More specifically the toggle joint 13 includes a bell crank lever 18^a and a link 19^a, while toggle joint 14 includes similar parts designated by reference characters 18^b and 19^b. The bell crank levers 18^a and 18^b are each provided with arms 20 and 21 and said levers are rotatably mounted upon shaft 16 and are arranged in opposed relation upon opposite sides of cam member 12 as shown 70 in Fig. 5. The lower ends of the links 19^a and 19^b are pivotally secured to lever 8 on opposite sides of shaft 9 by pins 22 and each of said links has its upper end pivotally secured to the arm 21 of its associated bell 75 crank lever by a pin 23. As shown in Fig. 5, operating member 12 is provided with arms having oppositely disposed projecting lugs 24-24 on the ends thereof and the arms 20 of the bell crank levers have forked projections 25 on the ends thereof for receiving said lugs. Also as shown in Fig. 1 each of the arms 20 of the bell crank levers is provided with a projection 26 which is located 80 below the forked projection 24 and the arms 21 of said bell crank levers are provided with cooperating stop projections 27.

The spring pressure device 15 includes a helical spring 28 slidably mounted upon a curved rod 29, said rod being arranged con- 100

centric with respect to the axis of shaft 16 and being secured at opposite ends to the lugs 24 on operating member 12. Spring 28 is held under compression between a pair of washers 30^a and 30^b slidably mounted upon the rod 29, the former washer being arranged between the projections 25 and 26 on bell crank lever 18^a and the latter washer being arranged between the projections 25 and 26 on bell crank lever 18^b.

10 The operation of the aforescribed mechanism will now be set forth.

15 With the parts of the operating mechanism positioned as shown in Fig. 1 it is apparent that if a force is applied to contact element 1 tending to rotate the same in a clockwise direction the links 19^a and 19^b tend to move the arms 21 of bell crank levers 18^a and 18^b towards each other. However, such movement of the arms 21 is prevented by engagement of the stop projections 27 thereon and contact element 1 is thus positively locked in the position shown to maintain bridging contact 2 in closed position and bridging contact 3 in open position.

20 Also it should be noted that with stop projections 27 in engagement as shown in Fig. 1 a force tending to move bell crank lever 18^a in a clockwise direction also tends to move the bell crank lever 18^b in a corresponding direction. However, as is apparent bell crank levers 18^a and 18^b cannot be moved simultaneously in a clockwise direction since the links 19^a and 19^b then produce opposing 25 forces on lever 8. Bell crank lever 18^a is therefore positively locked against movement in a clockwise direction out of the position shown in Fig. 1. Thus upon rotation of cam member 12 in a clockwise direction 30 out of the position shown in Fig. 1 spring 28 will be compressed since the left hand end thereof is held stationary by engagement of washer 30^a with the forked projection 25 on bell crank lever 18^a while the 35 right hand end thereof is moved downwardly by the right hand end of said operating member.

40 Upon rotation of operating member 12 into the position shown in Fig. 2 washer 30^a engages the projection 26 on bell crank lever 18^b and upon continued movement of said operating member in a clockwise direction said washer rotates said bell crank lever in a corresponding direction through the 45 position shown in Fig. 3. Upon movement of bell crank lever 18^b from the position shown in Fig. 2 into the position shown in Fig. 3 spring 28 is still further compressed and the arm 21 of said bell crank lever is moved into alinement with the link 19^b, such movement resulting in a slight counterclockwise rotation of contact element 1. As is apparent, upon rotation of bell crank lever 18^b in a clockwise direction beyond the position shown in Fig. 3 contact element 1 is

released to permit movement thereof in a clockwise direction out of the position shown in this figure. Upon release of contact element 1 by toggle joint 14 bell crank lever 18^a of toggle 13 is rotated in a clockwise 70 direction with a snap action by spring 28 from the position shown in Fig. 3 into the position shown in Fig. 4. Arm 21 of bell crank lever 18^a then acts through the medium of link 19^a to rotate contact element 1 75 from the position shown in Fig. 3 into the position shown in Fig. 4 with a snap action to thereby move bridging contact 3 into closed position, and bridging contact 2 into open position.

80 With the operating mechanism in the position shown in Fig. 4 operating member 12 is rotatable in a counterclockwise direction to effect snap movement of contact element 1 from the position shown in Fig. 4 85 into the position shown in Fig. 1. During such movement of operating member 12 the operation of the mechanism is the reverse of that hereinbefore described. As is apparent, when the parts are in the position shown in 90 Fig. 4 the toggles 13 and 14 cooperate in a manner similar to that described in connection with Fig. 1 to positively lock contact element 1 and bell crank lever 18^b against rotation in a counterclockwise direction out 95 of the position shown. During initial movement of the operating member 12 out of the position shown in Fig. 4 the right hand end of spring 28 is held stationary by engagement of washer 30^b with the forked projection 25 on bell crank lever 18^b while the 100 left hand end of said spring is moved downwardly by the left hand end of operating member 12. Spring 28 is thus compressed and upon engagement of washer 30^b with projection 26 on bell crank lever 18^a operating member 12 is adapted to move said bell crank lever through a position wherein arm 21 thereof is in alinement with link 19^a. Contact element 1 is thus released to permit 105 rotation thereof in a counterclockwise direction and spring 28 is then adapted to act through the medium of the parts of toggle 14 to return contact element 1 from the position shown in Fig. 4 to the position shown 110 in Fig. 1 with a snap action.

115 In the embodiment illustrated operating member 12 is designed to be actuated by a nut 31 mounted upon a screw 32. The arms of operating member 12 are provided with cam surfaces 33 and 34 having faces 35 and 36, and as is apparent said faces are adapted to be engaged by nut 31 upon movement of the latter between the positions shown in Figs. 1 and 4 to effect rotation of operating member 12 in opposite directions.

120 What I claim as new and desire to secure by Letters Patent is:

1. In a switch mechanism, the combination with a pivoted contact element, of a pair 125

- of toggle joints associated with said element for operating the same in opposite directions, and means including a spring pressure device for actuating said toggle joints to provide for actuation of said contact member in opposite directions with a snap action. 5
2. In a switch mechanism, the combination with a pivoted contact element movable in opposite directions between given circuit controlling positions, of a pair of toggle joints associated with said element and connected thereto on opposite sides of the pivot thereof, each of said toggle joints being movable in one direction through its straightened position to effect movement of said contact element into one of its circuit controlling positions and to lock the same in such position, and means including a pivoted operating member movable in opposite directions to 10 actuate said toggle joints for movement of said contact member in opposite directions between its circuit controlling positions with a snap action. 15
3. In a switch mechanism, the combination with a pivoted contact member requiring movement in opposite directions between given circuit controlling positions, of a pair of toggle joints associated with said member and connected thereto on opposite sides of the 20 pivot thereof, each of said toggle joints being movable in one direction through its straightened position to effect movement of said contact member into one of said circuit controlling positions and to positively lock the same 25 against movement out of such position, an operating member movable in opposite directions to positively operate said toggle joints for release of said contact member in said circuit controlling positions and spring means 30 associated with said member for actuating said toggle joints to provide for operation of said contact member in opposite directions between its circuit controlling positions with a snap action. 35
4. The combination with a pivoted member to be moved in opposite directions between given positions, of a pair of toggle joints connected to said member on opposite sides of the pivot thereof, each of said toggle 40 joints when straightened being adapted to move said member into one of said given positions and to lock the same therein and means for operating said toggle joints to provide for actuation of said member in opposite directions between said given positions with a snap action. 45
5. The combination with a pivoted member movable in opposite directions between given positions, of a pair of operating toggles associated therewith, each of said operating toggles being movable in one direction through its straightened position to move said member into one of said given positions and to positively lock the same therein, means 50 for positively moving either of said toggles 55 in a direction to release said member, and means associated with said former means for operating either of said toggles with a snap action upon release of the other of said toggles by said member. 60
6. The combination with a pivoted contact member movable in opposite directions between given circuit controlling positions, of a pair of operating toggles associated therewith, each of said toggles being movable in one direction through its straightened position to move said contact member into one of said circuit controlling positions and to positively lock the same therein, an operating member movable in opposite directions to positively actuate said toggles for release of said contact member in either of its circuit controlling positions, and spring means associated with said operating member and adapted to act upon release of said contact member by either of said toggles to move the other of said toggles through its straightened position with a snap action. 70 75 80 85
7. The combination with a pivoted contact member movable in opposite directions between given circuit controlling positions, of a pair of operating toggles associated with said member and connected thereto on opposite sides of the pivot thereof, a common supporting shaft for said toggles, each of said toggles being movable in one direction upon said shaft through its straightened position to move said contact member into one of said circuit controlling positions and to lock the same therein, an operating member rotatably mounted upon said shaft and adapted upon rotation in opposite directions to positively actuate said toggles for release of said contact member in said circuit controlling positions, and spring means associated with said operating member and adapted to act upon release of said contact member by either of said toggles to move the other of said toggles through its straightened position with a snap action. 90 95 100 105 110
